(57)

CLAIM

The ornamental design for an exit sign as shown and described.

DESCRIPTION

FIG. 1 is an isometric view of an exit sign showing our new design;

FIG. 2 is a front elevational view thereof showing ornamental features related to a camera, a display, an "EXIT" sign, and color coded notification lights;

FIG. 3 is a bottom plan view thereof;

FIG. 4 is a right elevational view thereof showing ornamental features related to a flashing light and a speaker;

FIG. 5 is a rear elevational view;

FIG. 6 is a left side view thereof showing ornamental features related to a flashing light and a speaker; and,

FIG. 7 is a top plan view thereof.

The broken lines depict portions of the exit sign and form no part of the claimed design.

1 Claim, 4 Drawing Sheets
